(57) **CLAIM**

The ornamental design for a combined paper scoop and plastic dipping station, as shown and described.

DESCRIPTION

FIG. 1 is a top perspective view of the design of a combined paper scoop and plastic dipping station showing the new design;

FIG. 2 is a front elevation view of the combined paper scoop and plastic dipping station shown in FIG. 1;

FIG. 3 is a rear elevation view of the combined paper scoop and plastic dipping station shown in FIG. 1;

FIG. 4 is a right side elevation view of the combined paper scoop and plastic dipping station shown in FIG. 1 (the left side elevation view of the combined paper scoop and plastic dipping station is a mirror image of the view shown in FIG. 4);

FIG. 5 is a top plan view of the combined paper scoop and plastic dipping station shown in FIG. 1; and,

FIG. 6 is a bottom plan view of the combined paper scoop and plastic dipping station shown in FIG. 1.
